UNITED STATES PATENT OFFICE

WILLIAM HERTZBERG, OF BROOKLYN, NEW YORK

MACHINE FOR MAKING TUFTS ON WIRE BRUSHES

Application filed October 3, 1927. Serial No. 223,732.

This invention relates to improvements in the manufacture of twisted wire brushes and to special means used in the process of making such brushes.

5 In particular this invention refers to the manufacture of twisted wire brushes as are used for cleaning bottles and the like and the specific object of this invention is the forming of a tuft at the end of each brush.

10 These tufts have heretofore been formed by hand and my invention is embodied in a machine for forming these tufts.

It is an object of the invention to produce the tufts quicker, more uniform in size and 15 more safely tied than by hand work.

It is another important object of the invention to safeguard the hands of the operator which are often injured by the binding wire when tying tufts by hand, this danger is eliminated by my invention.

20 With these and other objects in view the invention consists in a novel machine for the purpose above specified embodying a novel combination of devices to obtain its objects; 25 all as hereinafter described and finally pointed out in the appended claims.

In the accompanying drawings which form a material part of this disclosure:

30 Fig. 1 is a front elevation of the machine.

Fig. 2 is a top plan of the machine.

Fig. 3 is a vertical elevation on line 3—3 of Fig. 1.—Parts are shown in section as indicated by said line.

35 Fig. 4 is a vertical section on line 4—4 of Fig. 2 similar to Fig. 3 but the vertical twisting shaft 45, is turned 90 deg.

Fig. 5 is a sectional end elevation of the machine on line 5—5 of Fig. 1.

40 Fig. 6 is a detail elevation showing a brush inserted in the machine for tuft forming.

Fig. 7 is a detail section at line 7—7 of Fig. 6, showing a side elevation of stem guide 55.

45 Fig. 8 is a side elevation of a brush showing a finished tuft thereon.

Fig. 9 is a plan on line 9—9 of Fig. 3, showing the tuft forming jaws 49—50 in section through aperture 53a.

50 Referring to the drawings Fig. 8 illustrates a twisted wire brush 15 on which 15a is the

tuft, the product of the machine embodying the invention.

The brush 15 including its stem 15b is formed by other means which do not form a part of this disclosure. Before the tuft 55 forming operation is begun the wires which form the stem 15a end at the plane indicated by line 8—8 of Fig. 8. They are covered by bristles up to that plane, and these bristles are in a position like the other brush-forming 60 bristles, radiating outwardly from the stem 15b.

In Fig. 1 numeral 20 indicates a plate suitably supported on legs 21. Plate 20 supports a pillow block 22 supporting at its upper end a journal 23 in which the horizontal shaft 24 rotates by means of hand operated fly wheel 25. A bracket 26 on block 22 holds a vertical rod 27 with fork 27a at its upper end. The lower part of rod 27 is of reduced diameter, surrounded by a helical spring 28 and guided in an aperture of table 20. Spring 28 presses fork 27a against shaft 24 and produces a braking action against shaft 24 to prevent its spinning.

The front part of shaft 24 supports the wire-guide-arm 30 which carries in a fork-shaped portion a wire reel 29 which contains binding wire 31 for tying the tufts. The guide arm 30 is fastened to shaft 24 and rotates with the same while reel 29 rotates on shaft 24. A spring 29a prevents reel 29 from spinning freely. The horizontal part of arm 30 supports the wire 31 and guides it to the twisting mechanism, for this purpose arm 30 is provided with apertures 32 and a slot 33 in its inclined nose piece 30a. There is also a spring 34 mounted on arm 30 which may be tightened against wire 31 by means of screw 35 to adjust the tension of the wire.

To the lower side of table 20 two pillow blocks 40 are attached extending vertically downward therefrom. These blocks hold a horizontal shaft 41 journalled in their bearings. To one end of this shaft a hand wheel 42 is fastened and to the other end a bevel gear 43, which meshes into a bevel pinion 44 and drives a vertical twisting shaft 45. Ball thrust bearings 46 and a journal 47 hold shaft 45 rotatably on table 20. The axis of

shaft 45 if extended would pass through the slot 33 and tip of nose piece 30^a. An angular plate 48 is fastened to the upper end of shaft 45. The vertical portion of this plate carries the tuft forming jaws 49 and 50 of which 49 is rigidly fastened to 48, and 50 oscillatably mounted thereon on pivot 51.

The tuft forming jaws are held in closed position by means of a helical tension spring 52 attached to the lever 50^a (see Fig. 3). An inward pressure against 50^a opens the slot 53 and aperture 53^a in jaws 49 and 50. Aperture 53^a is in axial alinement with shaft 24. A horizontal guide bracket 54 is fastened to plate 48 whereon the stem support 55 is slidably mounted and can be fastened to bracket 54 by means of a thumb screw 56. Stem support 55 consists of two flat springs which lie tight against each other in their lower portion and form a cylindrical guide 55^a in axial alinement with the aperture 53^a of the tuft forming jaws 49 and 50 and with the axis of shaft 24. The free end of the two springs are bent outwardly to form lips 55^b acting as entrance guide for the stem of a wire brush 15, they facilitate the separation of the springs by the brush-stem 15^b when the operator presses it downward into the guide 55^a.

The front faces of angular plate 48 and of jaws 49 and 50 are held perpendicular to arm 30 by means of a horizontal stop-plate 70 provided with a shallow recess at its front end which engages the narrow side of plate 48. Stop plate 70 is held above table 20 by a block 71 upon which it slides being held thereon by studs 72 which pass through slotted apertures in plate 70. A vertical leg 70^a on plate 70 is pressed against block 71 by a helical compression spring 73 which leans against the head of a stud 74. This stud is held in block 71 and passes through an aperture in leg 70^a. When plate 48 rotates about the vertical axis of shaft 45 it alternately escapes from the recess in plate 70 and is arrested thereby as soon as it returns to a position perpendicular to arm 30.

The operation of the machine is as follows:

The operator opens the tuft-forming jaws 49 and 50 by pressing lever 50^a of Fig. 3 towards the left. He inserts a twisted wire brush 15 between these jaws as shown in Fig. 6 so that the front end 15^c of the stem and a part of the bristles extend beyond the tuft forming jaws whereupon he releases lever 50^a and spring 52 closes jaw 50. He presses the main part of the stem 15^b between the springs 55 to enter into guide 55^a. He adjusts stem support 55, sliding it on bar 54 so that a distance of free stem remains between the bristles forming the brush and support 55. This distance is shorter than the distance which end 15^c protrudes beyond jaws 49 and 50. When the brush is properly placed in the machine the operator pulls the stem and brush backward so that the bristles touch

the support 55 as shown in Fig. 1 and turns the brush slightly on its axis during this operation. Hereby the tuft 15^a at the front end of the brush is formed as the bristles in front of jaws 49 and 50 are bent into horizontal position in passing through the aperture 53^a. To facilitate this bending the forward portion of aperture 53^a is lightly rounded as indicated in Fig. 9. As the brush was not pulled back as much as the stem protruded beyond the jaws 49—50 a part thereof will still protrude therefrom and form a core for the tuft 15^a. The operator then holds the end of binding wire 31 between the two fingers of his left hand approximately at *a* (Figs. 6 and 1) and turns hand wheel 25 a few revolutions; this turns arm 30 around the brush axis and winds the binding wire 31 tightly upon the stem end 15^c which protrudes beyond jaws 49—50 and upon the bristles of the tuft 15^a with which it is covered. When the tuft is sufficiently tied in this manner the operator stops turning wheel 25 and starts to turn hand wheel 42 still holding the end of binding wire at *a*. The turning of wheel 42 rotates the vertical shaft 45 with angular plate 38, the stem support 54, brush 60 and jaws 49—50 about the continuation of the axis of shaft 45, which passes along the front side of jaws 49—50 to the tip of nose 30^a of arm 30. This rotary movement twists a part of the binding wire lying between tuft 15^a and point *a* about the other part of binding wire which extends from nose piece 30^a to the tuft 15^a about which it was previously twisted. In this manner the tuft is securely tied and the wire prevented from unraveling. The operator then cuts the binding wire at line *b* of Fig. 4 and bends the twisted binding wire to lie flat against the solid portion of the tuft having its ends imbedded between the radial bristles. The brush is then removed from the machine. The whole operation of forming a tuft requires only a few seconds of time.

Having thus described my invention what I claim is new and wish to secure by Letters Patent is:

1. In a machine of the kind described, a frame, a holder adapted to support a brush having a stem and brush material surrounding the stem, a shaft on said frame, the stem of a brush in said holder being in axial alinement with said shaft, and means on said holder for dividing the brush material into parts and for shaping a tuft from one part of the brush material and means on said shaft for coiling wire upon the tuft shaped by said holder.

2. In a machine of the kind described a frame, a holder adapted to support a brush having a stem and bristles radiating transversely therefrom, a shaft on said frame, the stem of a brush in said holder being in axial alinement with said shaft, means for separat-

ing the bristles into two parts and for drawing one part thereof over one end of said stem by sliding the brush in its holder forming a tuft and means rotated by said shaft for coiling wire upon the bristles of the tuft.

5 3. In a machine of the kind described the combination of a frame, a holder adapted to support a cylindrical brush having a stem and bristles radiating therefrom, a shaft on said frame, the stem of a brush in said holder being in axial alinement with said shaft, wire coiling means rotated by said shaft and means to rotate said holder about an axis perpendicular to said shaft.

15 4. In a machine of the kind described, a holder adapted to hold a brush having a stem and bristles radiating therefrom, a guide on said holder for slidably supporting said stem, supporting means holding a binding wire, a pair of shaping jaws for separating the bristles of the brush and for forming a tuft from one part thereof by the sliding said stem in its guide and rotary means for winding the wire upon the tuft formed on the brush.

25 5. In a machine of the kind described, the combination of a support adapted to hold a brush having a stem and bristles radiating transversely therefrom forming a cylindrical brush, means for forming a part of the bristles into a tuft covering the end of the stem, a wire winding mechanism holding binding wire and forming means for coiling the wire around a part of the tuft and a wire twisting mechanism for twisting the ends of the binding wire about each other.

35 6. In a machine of the kind described a frame, a holder supporting a cylindrical brush having a stem and brush material surrounding the stem, a shaft on said frame, the stem of a brush in said holder being in axial alinement with said shaft, an arm for guiding wire to said holder, means for rotating said shaft to wind the wire guided by said arm upon the stem and the brush material, and means for rotating said holder to twist portions of the binding wire about each other.

45 7. In a machine of the kind described a holder supporting a cylindrical brush having a stem and brush material radiating therefrom, means on said holder for shaping a tuft from the brush material to cover the end of the stem, an arm for guiding binding wire to one end of the brush-stem, means for winding the wire around the tuft and means for twisting portions of the wire about each other.

55 8. In a machine of the kind described a frame, a shaft rotatably mounted thereon, a wire guiding arm rotated by said shaft, a brush holder adapted for mounting a brush stem in axial alinement with said shaft, a spindle on said frame for rotating said holder perpendicular to said shaft, said guide arm forming means to wind wire upon a brush in said holder and said spindle form-

ing means by its rotation to twist portions of the binding wire about each other.

9. In a machine of the kind described a brush holder comprising a guide adapted to mount the stem of a brush for rotary and longitudinal movement, a pair of jaws on said holder, recesses in both jaws in juxtaposition forming together an aperture the walls of which have a tapered portion to engage brush material placed between said jaws and to form means for shaping a tuft at the end of the brush-stem by sliding the stem in said guide longitudinally.

70 10. In a machine of the kind described a holder supporting a cylindrical brush having a stem and brush material radiating therefrom, said holder comprising a bar, means forming a bearing for the bare part of the brush-stem slidably mounted on said bar and a pair of jaws on said holder forming a second bearing for the brush covered portion of the stem, one of said jaws being resiliently mounted forming with the other jaw yielding means to shape a part of the brush material into a tuft at the end of the stem.

75 11. In a machine of the kind described a frame, a pair of shafts rotatably mounted on said frame, said shafts having their axes in a common plane perpendicular to each other, a brush holder mounted upon one of said shafts and means on the second shaft for coiling wire upon a brush in the said holder.

80 12. In a machine of the kind described, a frame, a shaft rotatably held on said frame, a brush holder mounted on said shaft perpendicularly to its axis, means for coiling wire upon a brush in said holder and means to rotate said holder and the brush therein for twisting the ends of wire at the brush around each other.

85 13. In a machine of the kind described the combination of a frame, a pair of shafts rotatably held thereby, said shafts having their axes in a common plane perpendicular to each other, a brush holder at the end of one of said shafts forming means to rotate a cylindrical brush about an axis perpendicular to its own axis, means rotated by the second shaft for winding wire upon said brush and other means to stop the rotary movement of the brush holding shaft when the brush axis is in the common plane of both shafts.

90 In testimony whereof, I have signed my name this twenty-third day of September, 1927.

100 WILLIAM HERTZBERG.
